(57) **CLAIM**

The ornamental design for a sharpener with eraser, as shown and described.

DESCRIPTION

FIG. 1 is an exploded perspective view of a sharpener with eraser, embodying my new design;

FIG. 2 is a front, top, right side perspective view thereof with the cap engaged;

FIG. 3 is a front, top, right side perspective view thereof without the cap;

FIG. 4 is a front elevational view of FIG. 2;

FIG. 5 is a front elevational view of FIG. 3;

FIG. 6 is a rear elevational view of FIG. 2;

FIG. 7 is a rear elevational view of FIG. 3;

FIG. 8 is right side elevational view of FIG. 2; the left side elevational view being a mirror image thereof;

FIG. 9 is a right side elevational view of FIG. 3; the left side elevational view being a mirror image thereof;

FIG. 10 is a top plan view of FIG. 2;

FIG. 11 is a top plan view of FIG. 3;

FIG. 12 is a bottom perspective view of FIG. 2;

FIG. 13 is a bottom plan view thereof; and,

FIG. 14 is a bottom view thereof with the sharpener door open.

The broken lines on the inside of the bottom in FIG. 14 are included for the purpose of showing features that form no part of the claimed design.

1 Claim, 5 Drawing Sheets
